UNITED STATES PATENT OFFICE.

ALTON L. BAUGHMAN AND DELMER L. BAUGHMAN, OF ALBION, INDIANA.

GRAIN-DRILL.

SPECIFICATION forming part of Letters Patent No. 450,478, dated April 14, 1891.

Application filed September 8, 1890. Serial No. 364,371. (No model.)

To all whom it may concern:

Be it known that we, ALTON L. BAUGHMAN and DELMER L. BAUGHMAN, both residents of Albion, in the county of Noble and State of Indiana, have invented certain new and useful Improvements in Grain-Drills; and we do hereby declare that the following is a full, clear, and exact description of the invention, which will enable others skilled in the art to which it appertains to make and use the same, reference being had to the accompanying drawings, which form a part of this specification.

Our invention relates to improvements in grain-drills.

The object of the invention is to provide improved means for causing the grain to be fed without variation in amount whether the drill is running straight or turning to the right or left, to provide means for throwing the feeding devices in and out of gear, to provide means for regulating the depth of drill, and to provide means for throwing the hoes into and out of line.

The invention also contemplates other objects and advantages, which will be apparent to those skilled in the art to which the invention pertains.

The invention consists in the novel construction and combination of parts herein-after fully described, and specifically pointed out in the claims.

In the accompanying drawings, Figure 1 is a plan view of a drill constructed in accordance with our invention, the wheels and hopper being removed. Fig. 2 is a side view of the same with the hopper in place. Fig. 3 is a sectional side elevation. Fig. 4 is a detail sectional view of the feed-wheel and cap, showing the position of the same in the hopper. Fig. 5 is an edge view of the feed-wheel. Fig. 6 is a rear view showing two grain-spouts coupled to a cup. Fig. 7 is a view of a portion of the hopper and the feed-shaft gears. Fig. 8 is an inside view of the hub of the loose driving-wheel, showing its pawl and the ratchet on the rotating sleeve. Fig. 9 is an inside view of one of the feed-wheel caps or cups. Fig. 10 is a detail view of a portion of one of the feed-wheels. Figs. 11 and 12 are detail views of the bearing for the shaft carrying the gear for operating the feed-wheel

shaft. Fig. 13 is a detail view of the segment at the rear of the machine.

In the said drawings the frame of the drill is shown as being composed of side bars 1 and transverse bar 2 and provided with a tongue 3.

The numeral 4 designates the axle which supports the driving-wheels 5 and 6, the driving-wheel 5 being fixed to the axle and revolving therewith, the axle at this side of the drill being journaled in a bearing 7 in the frame 1. At the opposite end the axle is provided with a sleeve 8, which revolves freely thereon and which passes through the hub of the driving-wheel 6, its end being received in a collar 9, secured in the end of the axle.

Intermediate of the inner side of the wheel-hub and the drill-frame and formed integral with sleeve 8 are the cog-wheel 10 and ratchet-wheel 12, the former of which meshes with a gear-wheel 13 on a shaft 14, while the ratchet-wheel engages with a pawl 15, secured to or connected with the wheel-hub, so that as said wheel revolves the gear 13 also revolves, so as to rotate the shaft 14 and, through the medium of the gears 14^a and 14^b, rotate the feed-shaft and the feed-wheels and arms, as will hereinafter be described. The sleeve 8 extends through the side bar 1 of the frame and at its inner end is provided with a ratchet-wheel 17, fixed thereto or formed integral therewith.

The numeral 18 designates a collar secured to the axle and abutting against ratchet 17 and carries a pawl 19 to engage with said ratchet to revolve the sleeve and actuate the feed-wheels when the axle revolves and the wheel 6 does not rotate—as, for instance, when turning.

The end of the shaft 14 which carries the cog-wheel 13 is journaled in a frame or casting 20, pivoted to an arm secured to the hopper, said frame having a rearwardly-extending arm 21, the end of which engages with a shoulder 22 on the upper end of a lever 23, pivoted in a bearing 24, secured to the side bar of the drill. The object of this lever 23 is to hold the gear 13 in mesh with cog-wheel 10 and prevent its displacement until thrown out of gear, as hereinafter explained, being provided with a coiled spring 23^a for such purposes. The lower end of the lever 23 is provided with a stud 25, which engages with

a slot 26 in the reciprocating bar 27, connected with a crank 28, secured to rack-bar 29. At its forward end this bar 27 is provided with a slot 30, with which engages a stud 31 of the 5 downwardly-dependant arm 32, formed integral with the frame 20, by means of which the cog 10 and gear 13 are thrown in and out of gear, as will hereinafter appear.

The numeral 33 designates the hopper, of 10 ordinary construction, secured to the drill-frame in the usual manner, and at its rear side near the bottom is the transverse feed-shaft 34, having at one end the gear 14^b, which meshes with gear 14^a on shaft 14.

15 At suitable intervals in the rear side of the hopper are the feed-wheel caps or cups 35, having openings 36 in each side. The feed-shaft 34 passes through these caps and carries the feed-wheels 37, each of which consists of a 20 central disk having a series of curved radial wings or ribs 38 on each face. The periphery of this disk extends beyond the ends of the wings or ribs, forming an annular flange 39, which fits in a similarly-shaped groove 40 in the cap 35, which will prevent the grain from getting between the disks and caps and becoming crushed and thus unfit for use. In the lower part of each cap is a lug 41, through which passes a pivot-pin 42, which carries the 25 feed-spouts 43, one on each side of the caps. These spouts are provided with the usual feed-tubes 44, of rubber or other similar material, which pass down through the ordinary teeth 45. It will thus be seen that one feed-wheel serves to feed the grain from the hopper to two delivery-tubes.

The teeth 45 at their upper ends are provided with forwardly-extending projections 46, each having a series of orifices 47, with 40 which are connected the drag-bars 48. These drag-bars are bifurcated at their forward ends and are alternately connected with the transverse eccentrically-journalized bars 49 and 50, mounted in the side bars 1 of the drill-frame.

45 At one end of the rear bar 49 is secured a lever 52, which is connected by means of a link 53 with a crank 54, secured to bar 50. The free end of lever 52 is connected with a rearwardly-extending bar 55, having a handle 56 50 and provided on its under side with a series of notches 57, which engage with a lug 59, secured to the hopper. By operating the bar 55 the transverse bars will be oscillated so as to bring their lower portions which carry the 55 drag-bars nearer to or farther from each other, and thus causing the teeth to lie in a straight or zigzag line, as will be obvious.

The teeth are supported at the rear by means of chains 45^a or adjustable arms secured thereto and to one end of the levers 60, secured to collars 61, which embrace and work loosely on the rock-bar 29. These levers also have backward extensions 62, by which they may be operated to regulate the depth of drilling. This rock-bar 29 is journalized in bearings in the side frame 1. The numeral 63 65 designates a segment-plate, the forward end

of which is secured to a beam or tongue 3, secured to the central cross-bar 2 of the drill-frame, and at its rear is formed with a series of ratchet-teeth 64, with which the spring-pawl 65 of the lever 66 engages. This lever is firmly secured to the rock-bar 29 and has a forwardly-extending arm 67, having a hooked end, which engages with a transverse bar 75 68, (see Fig. 1,) connected at each end with the rock-bar 29. This bar 68 lies a little in front of and below the bar 29 and is immediately underneath the front arms of the levers 60, so that as it is raised by lever 66 and bar 80 29 it will raise the front ends of levers 60 and elevate the teeth, so as to regulate the depth of drill.

The operation is as follows: As the drill moves forward the wheels 5 and 6 and the 85 axle will revolve, causing the sleeve 8, carrying the cog-wheel 10, to be rotated by means of the ratchet-wheels 12 and 17, engaging, respectively, with the pawls 15 and 19 on the hub of wheel 6 and on the axle. The revolution of cog 10 rotates gear 13 on shaft 14, and through the medium of gears 14^a and 14^b the feed-shaft and feed-wheels are rotated. When it is desired to turn the drill, say, to the left, with wheel 5 as a center, then this wheel and the axle to which it is fixed will not rotate. Wheel 6, however, will revolve, and by means of the pawl 15 and ratchet 12 the sleeve 8, upon which it is journaled, will revolve and the feed be kept up through the medium of gear 13 and connections. In turning in the opposite direction or to the right then wheel 6 will not revolve; but wheel 5 and the axle will rotate, and by means of the ratchet 17 and pawl 19 on the axle the said sleeve 8 will 95 continue to revolve and the feed-wheels to be actuated. It will thus be seen that the feed is continuous, whether the machine be running ahead or turning either to the right or to the left.

The teeth may be elevated or depressed to regulate the depth of drill either singly or collectively, as desired. To adjust them singly, it is simply necessary to elevate or depress the rear extensions of the levers 60, as 105 before set forth. To adjust the teeth collectively or simultaneously, the lever 66 is pushed backward, which will actuate the rock-bar 29, causing the bar 68, with which it is connected, to be raised, which in turn will raise the front 110 arms of levers 60, and consequently the teeth, through the chain with which they are connected to said levers. The pawl carried by lever 66 will engage with the ratchet-teeth 115 of the segment-plate 63 and retain the teeth 120 in their adjusted positions. To depress the teeth to drill deeper, the lever 66 is released, when the bars and teeth will drop by gravity.

To throw the gears 10 and 13 out of mesh, so as to stop movement of the feed-wheels, 130 the lever 66 is pushed still farther back toward the last notch in the segment-plate 63. This will cause the reciprocating bar 27 to be pushed forward until the stud 31 of the

downwardly-depending arm will strike the end of slot 30, causing the frame 20 to be raised and the gear 13 to be thrown out of mesh with cog 10. At the same time the stud 5 25 will come in contact with the end of slot 26, causing lever 23 to turn on its pivot and the arm 21 of frame 20 to be released from the shoulder 24, so as to allow said frame to turn on its pivot. To throw into gear again, the 10 lever 66 is released and the bar 27 drawn back, when the forward end of frame 20 will drop down by gravity, so as to bring gear 13 and cog 10 into mesh. At the same time lever 23 would be thrown into position by means of 15 its coiled spring 23^a. This lever also prevents breakage of the teeth of the gears 10 and 13 by preventing gear 13 from striking cog 10 until in position to properly mesh therewith.

20 In Figs. 11 and 12 we have shown an adjustable bearing for the shaft 14, the same consisting of a plate or bar 69, having a head 70, provided with a circular bore, through which the said shaft passes. This plate is 25 also provided with a longitudinal slot 71, through which passes a bolt 72, provided with a thumb-nut 73. This bolt also passes through the casting 75, which supports the hopper. It will be obvious that the plate may be adjusted longitudinally by means of the thumb-screw and bolt.

30 The gear 14^b on the shaft 14 is provided with a flange 14^c, which abuts against the inner side of the gear 14^a, thus obviating the 35 use of pins to secure the same to its shaft, as the flange will prevent its displacement until gear 14^a is removed.

Having thus described our invention, what we claim is—

- 40 1. In a grain-drill, the combination, with the frame, an axle having a pawl intermediate of its ends, and a driving or supporting wheel fixed to one end of the axle, of a sleeve loosely mounted upon the other end of the axle, and a driving or supporting wheel having a 45 pawl journaled on said sleeve, the sleeve being provided with ratchet-wheels at each end engaging, respectively, with the pawls on the axle and wheel, substantially as described.
- 50 2. In a grain-drill, the combination, with the frame, an axle having a pawl intermediate of its ends, and a driving or supporting wheel fixed to one end of the axle, of a sleeve loosely mounted upon the other end of the

55 axle, a driving or supporting wheel having a pawl journaled on said sleeve, the sleeve being provided with ratchet-wheels at each end engaging, respectively, with the pawls on the axle and wheel and an intermediate cog-wheel, a transverse shaft having gears, one 60 end of which meshes with the cog on the sleeve, and a feed-bar having feed-wheels and a gear meshing with the other gear on the transverse shaft, substantially as described.

3. In a grain-drill, the combination, with 65 the frame, the axle, the supporting-wheels, and the teeth, of a transverse rock-bar 29, located in the rear of the frame, a transverse bar 68, connected with said rock-bar and located in front thereof, a series of levers 60, 70 pivoted on the rock-bar and connected with the teeth, a lever 66, secured to the rock-bar 29, having a hooked end 67 engaging with the bar 68, and means for locking the lever in position, substantially as described. 75

4. In a grain-drill, the combination, with the frame, the axle, the supporting or driving wheels, and a cog-wheel driven by said wheels, of a pivoted frame carrying a transverse bar having a gear meshing with said 80 cog-wheel, said frame being provided with a downwardly-extending arm and a rearwardly-extending arm, a pivoted spring-lever having a shoulder engaging with said rearwardly-extending arm, a reciprocating bar having 85 slots with which studs on said arms engage, and a rock-bar having an operating-lever and a crank connected with the reciprocating bar, substantially as described.

5. In a grain-drill, the combination, with 90 the hopper, the feed-shaft, the feed-wheel cups secured to the hoppers, having interior annular grooves and side openings, and the feed-spouts, of the feed-wheels located on the feed-shaft in the feed-wheel cups, said wheels 95 consisting of a disk having radial ribs or wings on each face and a central peripheral flange fitting in the grooves in the feed-wheel cups, substantially as described.

In testimony that we claim the foregoing as 100 our own we have hereunto affixed our signatures in presence of two witnesses.

ALTON L. BAUGHMAN.
DELMER L. BAUGHMAN.
